UNITED STATES PATENT OFFICE.

GUSTAF GABRIEL BRING, OF PETERSFORS, SWEDEN.

APPARATUS FOR MAGNETIC SEPARATION.

No. 827,499.

Specification of Letters Patent.

Patented July 31, 1906.

Application filed February 10, 1905. Serial No. 245,030.

To all whom it may concern:

Be it known that I, GUSTAF GABRIEL BRING, a subject of the King of Sweden and a resident of Petersfors, Jernboås, in the 5 Kingdom of Sweden, have invented certain new and useful Improvements in Apparatus for Magnetic Separation, of which the following is a specification, reference being had therein to the accompanying drawings.

10 This invention relates to an apparatus for treating a mixture of magnetic and non-magnetic minerals or the like in such a manner as to separate the former from the latter.

The construction of the apparatus is based 15 on the principle that a paramagnetic body that is placed within the solenoid at one end thereof is immediately magnetized and drawn by the magnetic force toward the center of the solenoid.

20 According to the present invention the mixture of magnetic and non-magnetic grains or particles to be treated is fed into the preferably upright solenoid at the upper open end thereof, and the magnetic particles are attracted and moved toward the center of the solenoid or magnetic field. The power of the magnetic field is, however, so calculated that the attracted particles do not stop at the center of the field, but on account 25 of their gravity continue to move slowly downward. During the movement they are subjected to the action of powerful jets of water, which carry away the non-magnetic grains adhering to the magnetic particles.

30 Finally, the magnetic particles are carried off from the magnetic field through the lower open end of the solenoid. The non-magnetic grains are carried off from the magnetic field in the opposite direction—viz., 35 through the upper end of the solenoid.

40 As all the particles to be separated are brought into the magnetic field and exposed to the magnetic force for a comparatively long time, the loss of magnetic grains will be 45 very small, even if the grains of the material should be only 0.15 millimeter in diameter, or still less. At the same time the magnetic product on account of the powerful washing to which it is exposed will become very 50 pure—*i. e.*, free from any admixture of non-magnetic grains. The washing can be made very powerful without incurring the risk of washing away magnetic material, for the rapidity of the current is considerably reduced at the outlet by means of a funnel or other equivalent device placed within the solenoid.

The solenoid should have a certain predetermined field strength depending upon the permeability of each particular material, as 60 also upon the size of the grains. The former is known to be always substantially the same as far as magnetites are concerned, and thus the size of grains will, in fact, be determinative. If at a certain winding of the solenoid 65 a current strength of, say, fifteen amperes is necessary when the material is crushed into grains of a diameter of 0.15 millimeter or less, then in the case of a size of grains of, say, one millimeter the current strength 70 should not exceed five to seven amperes in order that the apparatus shall work in the most favorable way.

The drawing shows a vertical section of an apparatus constructed according to this invention.

1 is the solenoid, consisting of an inner brass drum 2 of cylindrical, conical, or any other suitable shape. Placed on the said drum is a winding 3, of insulated copper wire, 80 said winding being arranged in any suitable way, so that the center of the magnetic field either coincides with that of the inner drum or lies above or below it. The copper wire has the diameter and length necessary to 85 give the solenoid the field strength required. At the outer side the winding is covered with a mantle 4 of sheet-iron. Placed within the solenoid is a funnel 5, forming at the top an annular channel or space 6, having an outlet 90 7. Within the lower part of the funnel is a perforated tube 8, and the perforated wall of the lower portion of the funnel is surrounded by a mantle 9, said tube and mantle being furnished with water from the pressure-conduit 10, so that powerful jets of water are 95 thus pressed into the funnel. The narrowest portion of the funnel preferably has a mouth-piece 11, which leads to a discharge pipe or tube 12, connected with another tube 13, 100 provided with an inner nozzle 14, by means of which the water passing out through the tube 13 is accelerated by water under pressure from the tube or conduit 10.

The apparatus works in the following manner: The material to be treated is crushed to grains of a size of one millimeter and less (or still finer) and is fed through the channel and tube 15 into the funnel 5, previously filled with water. The non-magnetic grains are 110 immediately carried with the stream of water over the edge of the funnel down into the channel 6 and away through the outlet 7. The magnetic particles, on the contrary,

move rapidly down toward the middle of the solenoid, then continue to move slowly downward and are thereby exposed to the washing from the tube 8 and the mantle 9. Such non-magnetic grains as may still adhere to the magnetic particles are thereby washed away, and the washed magnetic product gradually sinks through the mouthpiece 11, the opening of which is to be measured corresponding to each particular ore, and finally the magnetic product is carried off through the tube 13. A jet of water from nozzle 14 accelerates the escape of the product from the magnetic field, if necessary.

Having now described my invention, what I claim as new, and desire to secure by Letters Patent, is—

1. In apparatus for magnetic separation, a substantially upright solenoid, a funnel placed therein adapted to contain a body of water and perforated at its lower end, a mantle surrounding said perforated part, a tube within the funnel and having its lower end perforated, said mantle and tube communicating with means for supplying water under pressure.

2. In apparatus for magnetic separation, a substantially upright solenoid, a funnel placed therein adapted to contain a body of water and perforated at its lower end, a mantle surrounding said perforated part, a tube within the funnel and having its lower end perforated, said mantle and tube communicating with means for supplying water under pressure, and a mouthpiece for the passage of the magnetic particles out of the funnel.

3. In apparatus for magnetic separation, a substantially upright solenoid, a funnel

placed therein adapted to contain a body of water and perforated at its lower end, a mantle surrounding said perforated part, a tube within the funnel and having its lower end perforated, and a discharge-pipe, said mantle, tube, and discharge-pipe communicating with means for supplying water under pressure.

4. In apparatus for magnetic separation, a substantially upright solenoid, a funnel placed therein adapted to contain a body of water and perforated at its lower end, a mantle surrounding said perforated part, a tube within the funnel and having its lower end perforated, said mantle and tube communicating with means for supplying water under pressure, and a channel at the top of the funnel adapted to receive the non-magnetic particles and remove the same from the apparatus.

5. In apparatus for magnetic separation, in combination, a solenoid, a funnel placed therein adapted to contain a body of water, means for producing an upward current in such body of water, means for feeding the material to be separated into the top of the funnel, a discharge-pipe adapted to carry off the magnetic particles, and means independent of the funnel for producing a jet of water to accelerate the passage of the magnetic particles through said discharge-pipe.

In witness whereof I have hereunto set my hand in the presence of two witnesses.

GUSTAF GABRIEL BRING.
